UNITED STATES PATENT OFFICE.

ABRAHAM M. NADELL, OF REVERE, MASSACHUSETTS.

GARMENT FASTENER.

1,425,038.

Specification of Letters Patent. Patented Aug. 8, 1922.

Application filed October 8, 1921. Serial No. 506,339.

To all whom it may concern:

Be it known that I, ABRAHAM M. NADELL, a citizen of the United States, and resident of Revere, county of Suffolk, State of Massachusetts, have invented an Improvement in Garment Fasteners, of which the following description, in connection with the accompanying drawing, is a specification, like characters on the drawing representing like parts.

This invention relates to garment fasteners and has for its object to provide a novel fastener which while capable of various uses has special advantages when used for securing a brassière to the corset to prevent the brassière from working up.

In order to give an understanding of my invention I have illustrated in the drawings a selected embodiment thereof which will now be described after which the novel features will be pointed out in the appended claim.

Fig. 1 of the drawings shows one use to which my improved garment fastener may be put.

Fig. 2 is a front view of the garment fastener.

Fig. 3 is an enlarged sectional view on the line 3—3, Fig. 2.

Fig. 4 shows a different manner of using the device.

In Fig. 1 I have illustrated a female figure wearing a corset 1 and a brassière 2 with a tab 3 having a garment fastener at its lower end designed to be attached to the corset so as to hold the brassière in proper place.

My improved garment fastening comprises a body portion 4 of sheet metal having a key-slot opening therein, the latter being formed with the aperture 5 of a size to receive the head 6 of a headed stud and also having a slot 7 communicating with the opening 5 and of a size to receive the neck 8 of the stud. The body portion 4 has formed integral therewith a locking portion 9 which is bent back on the body portion and is provided with a locking edge 10 that extends across the slot 7. This locking portion 9 is made so that its locking edge 10 rests against the face of the body portion and the part of the locking portion adjacent the edge 10 covers the aperture 5 as clearly seen in Fig. 2. This locking portion 9 is provided with two lateral wings or extensions 11 which extend beyond the

sides of the body 4 and which constitute finger pieces for releasing the locking edge from its locking engagement with the stud.

The garment fastener is provided with a slot 12 into which the end of the tab 3 may be sewed. In using the device, as shown in Fig. 1, the garment fastener will be attached to the particular stud on the corset 1 which is situated to hold the brassière in the desired position. The device is attached to the stud by inserting the head of the latter through the opening 5 and then moving the neck of the stud into the slot 7. The insertion of the head of the stud through the opening 5 brings the head against the locking portion 9 and supports the latter slightly from the body and as the neck of the stud is moved into the slot 7 or into the position shown in Figs. 2 and 3 the head 6 will be carried out from under the edge 10, and when this occurs the resiliency of the metal moves the edge 10 against the body 4 and in position to engage under the head 6, thus locking the stud in the slot.

With this form of garment fastener used for this purpose there is no danger that the tab 3 will become accidentally disconnected from the corset stud. When it is desired to disconnect the fastener from the stud the operator will grasp the finger piece extensions 11 and separate the locking portion 9 sufficiently from the body portion 4 to enable the head of the stud to move beneath the locking portion and into position to be withdrawn from the opening 5.

In Fig. 4 I have illustrated a different way in which the device may be used for the same purpose. The body 4 is shown as having a slot 13 situated beyond the stud-receiving slot and this slot is adapted to have the end of the tab 3 sewed thereinto as shown in Fig. 4. If the corset is of that type which laces in front, as illustrated in Fig. 4, then the garment fastener may be secured to the tab 3, as shown in said Fig. 4, that is, with the tab secured into the slot 13. In this case after the corset and brassière have been properly adjusted some strands of the lacing 14 may be placed in the space 15 between the body 4 and the locking portion 9, said body and locking portion constituting a hook member adapted to hook onto some of the lacing. When used in this way the device will function equally well in preventing upward move-

ment of the brassière and the resiliency of the locking portion 9 maintains the edge 10 against the body 4 so as to prevent the lacings from becoming disconnected from the device. The device, therefore, constitutes in effect a closed hook to receive the lacing.

Although I have shown the device herein as having both the slots 12 and 13 yet the device might be made with only the slot 12 10 if it was always to be attached to a stud rather than to a lacing.

I claim.

A garment fastening having a body provided with an opening to receive a headed stud and a slot extending from the opening and adapted to receive the neck of the stud, said body having integral therewith a lock-

ing portion which is bent back against the body and is formed with a locking edge which extends across said slot, the part of the locking portion adjacent said edge covering the aperture, whereby said locking edge is adapted to engage beneath the head of a stud occupying said slot thereby to lock the stud in the slot, said locking portion having wings extending laterally therefrom beyond the body, which wings constitute finger pieces by which the locking portion may be separated from the body sufficiently to release the stud.

In testimony whereof, I have signed my name to this specification.

ABRAHAM M. NADELL.
